UNITED STATES PATENT OFFICE.

CHARLES H. WILLIAMS, OF CLEVELAND, OHIO.

DIE FOR MAKING TURN-BUCKLES.

SPECIFICATION forming part of Letters Patent No. 332,127, dated December 8, 1885.

Application filed July 31, 1885. Serial No. 173,173. (No model.)

To all whom it may concern:

Be it known that I, CHARLES H. WILLIAMS, a citizen of the United States, residing at Cleveland, in the county of Cuyahoga and State 5 of Ohio, have invented certain new and useful Improvements in Dies for Making Turn-Buckles, of which the following is a specification, reference being had to the accompanying drawings.

10 This invention relates to dies for forming turn-buckles; and it has for one of its objects the production of a turn-buckle which shall be entirely free from longitudinal fins. Such fins have heretofore been produced by reason 15 of the employment of holding and other dies divided longitudinally into sections. Another object in view is to provide a mechanism that shall form a positively rigid support or anvil to resist the pressure of the header or plunger 20 upon the stock, instead of putting this holding function upon dies formed in sections, adapted to be separated, requiring forcible lateral pressure, and affording a limited end surface of contact with the stock to resist the 25 pressure of the header or plunger. Another object is to provide devices which in connection with a fixed inner die or anvil will prevent lateral spreading of the sides of the turn-buckle blank at the time the head portion or 30 portions are swaged to final shape by the header or plunger. Another object in view is to positively and accurately centralize the bore of the head of the turn-buckle relative to its sides, and to determine the size of its bore 35 so that it may be by simply reaming out the scale fitted for cutting the thread therein. A further object is to provide a header and mandrel of such a construction and having such a mode of operation in use that the head of 40 the turn-buckle is formed by compressing the stock inwardly upon the mandrel, in contradistinction to spreading it outwardly by means of a spreader or punch.

Other objects and advantages of my invention will appear in the following description, and the novel features thereof will be particularly pointed out in the claims.

Referring to the drawings, Figure 1 is a perspective of a buckle-blank before the lap-joints thereof are closed. Fig. 2 is an end elevation of the lap-joints; and Fig. 3, a similar view of the same with the lap-joints more

nearly closed, such being their position when the blank is placed in the dies for completion, as hereinafter described. Fig. 4 is a vertical 55 section on the line X of Fig. 6; Fig. 5, an end elevation, and Fig. 6 a side elevation, of the completed turn-buckle. Fig. 7 is a plan, and Fig. 8 a front elevation, of dies constructed in accordance with my invention. Fig. 9 is 60 a diagram illustrating relative proportions of the turn-buckle when completed. Fig. 10 is a central vertical section on the line Y of Fig. 8, showing the dies and blank in the positions they assume when forming the head of the 65 turn-buckle. Fig. 11 is a horizontal section through the axis of the mandrel and header, and embodying modifications hereinafter described. Fig. 12 is a plan of the modification illustrated in Fig. 11, the mandrel and 70 head of the turn-buckle being shown in dotted lines.

Like letters indicate like parts in all the figures of the drawings.

Referring to Figs. 7 to 12, A represents a 75 bed-plate provided with a groove, A', for the reception of an inner fixed die or anvil, B, which may be formed integral with the bed, or may be removably retained within said groove by means of a strap (and bolts A'') secured to the bed. The anvil or inner die, B, has a contour conforming to that of all of the inner surfaces of the turn-buckle which come in contact therewith, and at such points as are above the turn-buckle when being formed on 80 the anvil the latter is more or less sharply tapered, to permit a blank to be easily placed upon and removed therefrom. The end of the anvil presents a broad, solid, fixed surface, against which the head portion of the blank 85 rests and is interiorly formed. By slightly rounding the corners of the anvil, as at B', Fig. 7, a proper fillet is provided at the junction of the sides and head of the turn-buckle. 90

B'' represents an aperture in the end of the 95 anvil for the reception of the end of the mandrel C, the extreme end C' of which is sharply tapered to permit its easy entrance into and withdrawal from the anvil.

D represents the header, in which the mandrel C is mounted, or of which the mandrel C may be formed as a part. In this instance the header is bored for the reception of the mandrel, and the latter is screw-threaded into the 100

former, as at C², its end C³ being formed to provide a wrench-surface for firmly inserting the mandrel into the head. The forward end of the head is provided with a cavity the 5 walls of which are completely circular and inclined, as shown at D', so as to conform to the outline of the head of the turn-buckle. The characteristics of the concavity of the header are that it is substantially cone-shaped, 10 with the larger portion of the cone disposed at the end of the header, and so that no insets or recesses occur, which would impede the withdrawal of the header from the stock after operating thereon. Within the cavity of the 15 header the mandrel C is slightly tapered, simply and for the sole purpose of permitting its easy removal from a head when once formed, and so that the sudden cooling of the metal of the head shall not contract the same 20 firmly upon the mandrel. The mandrel C is in no sense a "punch" or "spreader," nor is it intended to operate as such, as the stock supplied for the head is, by reason of the tapering walls D' of the header or plunger, 25 closed inwardly around, against, and upon the mandrel. In fact, the blank is provided with a bore larger in diameter than that of the mandrel, so that the latter, instead of acting as a spreader, serves to determine exactly the 30 diameter of the bore of the head, by resisting the inward movement of the stock, produced by the concavity of the header.

One of the principal objects and novel features of my invention is that I employ a header 35 and mandrel so constructed and co-operating that the metal which forms the head is forced inwardly, instead of being spread outwardly, the former process affecting favorably the perfection of the welds, seams, or lap-joints 40 of the sides and the head, as it tends to force them together, while the latter process—that is, the employment of the spreader or punch—has a marked tendency to force them apart or separate them.

45 It is not absolutely necessary that the forward end of the mandrel should enter the aperture in the die B, as said mandrel may terminate at the end of the die or anvil B, as shown by dotted lines Z, Fig. 10, in which case the 50 aperture B² would be omitted, and the broad unbroken end surface of the die would be left intact. So, also, the mandrel may in that case be brought simply in contact with the die, or, if desired, it may not come actually 55 in contact therewith, but may permit a slight parting in the metal to be formed at that point, though the stock will not be forced between the end of the mandrel and the die to any material extent.

60 E, Figs. 7 and 8, represents side retaining-dies, which are mounted in ways E' on the bed-plate, to be moved laterally toward and from the anvil B, the left die in Fig. 7 being shown removed and the right die in contact 65 with the side of the anvil. The sole function and purpose of these side dies are to prevent

outward lateral expansion of the sides of the turn-buckle at the time the head is formed thereon, and they perform no function of holding the blank against longitudinal movement 70 away from the header when operating to form the head of the turn-buckle. The inner edges of the dies E are concaved, as at E², Fig. 8, to conform to the outline of the sides of the turn-buckle, and to permit an escape 75 for any surplus of stock in the head, to be forced into the sides, thus slightly elongating them.

Instead of the side retaining-dies, E, I may form retaining devices or extensions D² upon 80 or as a part of the header D, in which case the forward ends of said extensions are flared outwardly, as at D³, to prevent abrading the sides of the turn-buckle, and in this instance also the upper and lower edges, D⁴, of said 85 extensions are preferably, though not necessarily, constructed to come in contact with the sides of the fixed die or anvil B to serve in a measure as a guide to the header. It will readily be seen that said extensions will 90 prevent lateral expansion of the sides of the turn-buckle at the time that the header is operating upon the head thereof.

I consider the circular contour of the concavity in the header or plunger and its continuously slanted, beveled, or cone-shaped interior an important novel feature of my invention, and as possessing great advantages 95 in construction and in use.

In construction the header may be cast comparatively large and bulky, and by the use of a reamer of the proper size and outline of the head of a turn-buckle of a desired size such cast header may be readily fitted up for use, and when worn by use another reamer of the 100 next larger size may be used to fit said worn head for further use in making buckles of such larger size, whereby the cost of dies is reduced one-half, whereas oval and other dies require the slow and expensive process of hand-labor 105 to construct them, and when worn are thrown aside as worthless. Again, by reason of the cylindrical interior of the concavity of the head all the enlargements of the head of the turn-buckle are in front in the direction of 110 the movement of the header, so that no lateral parting of the header or of the dies is necessary to remove the same from the work or the work therefrom. In like manner the mandrels 115 C, when worn or damaged by fire-cracks caused by the heated metal pressed thereon, may cheaply be reduced from size to size until all practical worth of the same has been utilized. So, also, may the fixed dies or anvils B be 120 work over into smaller sizes, and the mandrel- 125 aperture thereof, when used, may be bushed or capped to receive such smaller mandrels so that all the parts employed which are liable to become worn permit a ready refitting of the same for further use, and great economy 130 is secured.

It is apparent that inner fixed dies or an-

vils of various sizes may be mounted upon the bed-plate to adapt my invention for use in producing turn-buckles of different sizes.

A thus far described, it will be noticed that the principal elements of my invention are, a fixed inner die or anvil, side retaining devices, a header, and a mandrel, these being constructed to operate as hereinafter more particularly described.

10 In this instance I produce a turn-buckle in which the sides F are oval, and their exterior contour is such as to conform to the completely circular outline of the heads G, while the bores G' of each of the heads is proportionate to the amount of stock disposed in the sides.

The circle y in Fig. 9 represents the bore of the head, while the full lines represent the stock in the sides. By this diagram it will be seen that there is a surplus of stock in the sides over and above that which is in a bolt or rod of a size suited to the turn-buckle, so that sufficient strength is provided in the turn-buckle to prevent weakness thereof when used with any rod or bolt adapted to it.

25 I wish it understood that I do not limit my invention to the exact proportions of the several parts of the turn-buckle produced, nor to the exact proportions of the dies and their concavities for producing the same.

30 By reference to Figs. 1 to 6, inclusive, it will be seen that the blank comprises two sides, F F, and heads G G, having the lap-joints F', whereby the two parts are united. Such lap-joints are, by any suitable means, brought to a nearly closed position, as shown in Fig. 3, when one or both ends of a blank are brought to the welding-heat and the blank is placed upon the fixed anvil B. The side dies, E, if used, are brought against the die B, so as to retain the sides F from lateral expansion, or this function may be performed by the extensions D² on the head D. After the blank is placed upon the anvil B the header, with its mandrel, is brought toward the anvil, the point of the mandrel entering the aperture B² thereof, if such aperture be employed, and the extensions D², being in advance of the concavity of the header, first arrive at their operative position to prevent lateral 45 outward expansion of the sides F, and the concavity in the header begins to compress the metal inwardly upon the mandrel C. As soon as the header has reached the end of its stroke, it is quickly withdrawn and the blank removed, and another blank submitted for the 55 same operation.

It is apparent that two headers may operate simultaneously upon a single blank, the inner die being of proper length for each size 60 of the blanks made.

I have not shown any mechanism for giving

the proper motion to the movable parts employed, as this is a matter within the skill of persons conversant with the construction of metal-working machinery.

65

Having described my invention and its operation, what I claim is—

1. In a machine for forming turn-buckles, an integral inner die or anvil conforming to the interior of the head portion of a turn-buckle, substantially as specified. 70

2. In a machine for forming turn-buckles, an integral inner die or anvil and a header operating longitudinally against the turn-buckle blank mounted on said anvil, substantially as specified. 75

3. The combination of a fixed inner die or anvil, a header, and side-retaining devices, substantially as specified.

4. A header provided with side-retaining extensions conforming to the sides of a turn-buckle, substantially as specified. 80

5. An integral inner die or anvil and a header, in combination with side-retaining devices adapted to bear against said inner die or anvil, substantially as specified. 85

6. The combination of a fixed integral inner die or anvil, a movable header operating to force metal inwardly, and a mandrel operating to limit the inward movement of the metal, substantially as specified. 90

7. A fixed undivided inner die or anvil conforming to the interior outline of a turn-buckle, in combination with an undivided heading-die having a concavity circular in all of its cross-sections, and having a mandrel whereby longitudinal fins on the sides and head of a turn-buckle, either interiorly or exteriorly located, are obviated, substantially as specified. 95

8. An integral undivided heading-die having a concavity circular in all of its cross sections, and a concentric mandrel, whereby the formation of insets, recesses, and fins by said die upon the head of a turn-buckle is prevented, substantially as specified. 100

9. The combination of the die D, having the concavity D', circular in all of its cross-sections, the mandrel C, and extensions D², with the fixed die B, having the aperture B², substantially as specified. 105

10. The combination of the bed-plate A, having the groove A', the removably-fixed inner die, B, having the aperture B², and the head D, having the mandrel C, substantially as specified. 110

In testimony whereof I affix my signature in presence of two witnesses.

CHARLES H. WILLIAMS.
